GAS ANALYZING APPARATUS

Albert F. Spitzglass and George W. Grisdale,
Chicago, Ill., assignors to Republic Flow Meters
Company, Chicago, Ill., a corporation of Illinois

Application February 5, 1936, Serial No. 62,420

6 Claims. (Cl. 23—256)

This invention relates to apparatus for treating gases with liquid reagents and the like, as for example gas analyzing instruments, and is illustrated as embodied in a CO₂ recorder. This particular recorder is of the type in which the amount of CO₂ is determined by measuring the residual volume of a measured quantity of flue gas or the like, after absorbing the CO₂ in a reagent such as sodium or potassium hydroxide solution.

An object of the invention is to provide an apparatus which functions accurately and automatically, which is not substantially affected by temperature fluctuations, in which the gas (both before and after treatment by the reagent) is at room temperature and at atmospheric pressure so that no corrections are necessary, and which preferably has the gas analyzing devices arranged in a readily removable unit to facilitate calibration and repair.

One important feature of the invention relates to utilizing the reagent bath to cool the flue gases which are to be analyzed, for example by passing the gases through a coiled conduit or other form of heat exchanger submerged in the reagent.

The cooled gases are then passed, at atmospheric pressure, to a novel sampling device which is preferably arranged above the reagent, and which measures off definite quantities of the gas for treatment by the reagent. This device in itself embodies substantial novelty, especially in the arrangement of a vertically reciprocated container which measures off the gas and which is then forced down into a bath of mercury which serves the purpose of a simple and effective pump for forcing the measured quantities of gas down into and through the reagent, which acts on them to absorb the CO₂ content. The gas-measuring container is shown carried by a novel head which is provided with improved one-way valve means to control the flow of the gas.

A related feature of novelty has to do with the use of a vertical conduit into which the cooled gas is discharged by the heat exchanger submerged in the reagent, and which delivers gas at atmospheric pressure from its upper end to the above-described head, while the excess gas exhausts out at the lower end.

The means for measuring the residual gas, after treatment by the hydroxide bath or other reagent, embodies several novel features of structure and arrangement, one of which has to do with sealing the measuring means by a portion of the reagent which is always at the same level regardless of the level of the reagent bath, to in-

sure that the measurement is always at the same gas pressure.

An important feature, which we prefer to use in conjunction with those described above, has to do with the arrangement of the gas-treating parts of the apparatus in a separate unit which is readily removable as such, for calibration or repair.

The above and other objects and features of the invention, including various novel constructions and desirable arrangements, will be apparent from the following description of the illustrative embodiment shown in the accompanying drawings, in which:

Figures 1 and 2 are vertical sections, at right angles to each other, of a CO₂ recorder, with most of the parts appearing in elevation;

Figure 3 is a sectional diagram, with the various parts shown side by side to facilitate an understanding of their co-operative action;

Figure 4 is a partial section showing the pen-operating means;

Figures 5 and 6 are diagrams corresponding to Figure 3, but at different points in the cycle;

Figures 7 and 8 are sectional views of the one-way gas-controlling valve means, in different positions; and

Figures 9 and 10 are sections on the line 9—9 of Figure 3 showing the gas-measuring means respectively attached and detached.

The instrument illustrated comprises a panel or complete or partial outer casing 10 supporting at its upper end a vertical motor 12 driving a gear reduction device 14 of any desired character, shown with filler means 15 for filling with oil to a predetermined level. The gear reduction device 14 drives an operating shaft 16 having at one end an arm 18 connected by a vertical link 20 to a gas-measuring device hereinafter described.

The other end of the shaft 16 carries a double arm 22 carrying two cam rollers, one acting on a pivoted lever 24 against the resistance of a spring 26 to reciprocate a connecting rod 28 to operate a seal for the discharge of the final gas measuring means, and the other operatively engaging the upper end of a pivoted lever 30. The lever 30 is centrally fulcrumed on a rib 32 integral with or secured to the casing of the gear unit 14. Its lower end is operated, as hereinafter described, at the proper time in the cycle to release the pen arm or indicator of the instrument so that it may take up a new position indicating the percentage of CO₂ in the last sample.

The gear reduction device 14 also drives a

gear pump 34 (Figure 3) in an auxiliary casing 36 (Figure 1) which acts to draw flue gases, or other gases to be analyzed, through a conduit 38 (having a glass vessel 40 partly filled with water, to give a visual indication, if desired) from any desired source of such gases. Condensed moisture drips down into and overflows from, a pipe 41 bent to provide a seal or trap at its lower end. The gases pass from the pump into the upper 10 part of a container 42 provided with a drain plug 44, which is filled to a predetermined level with oil.

Passages 46 and 48 may be provided into the container 42, also, from the conduit 38 and the neutral point of the pump 34, these passages opening below the normal level of the oil in container 42. This serves to circulate oil through the pump, to seal it. The container 42 may have suitable filler means 50.

20 The gases next pass through a conduit 52 and, according to an important feature of the invention, pass through a heat exchange device (illustrated as a coil 54 forming a continuation of the conduit) submerged in a liquid reagent 56 in a 25 reservoir 58.

As explained below, in analyzing flue gases for CO₂ content, this reagent would be a solution of caustic potash or soda. The amount of this reagent and the size of the container or reservoir 30 58 are such that heat is dissipated into the room a fast as it is absorbed from the flue gases, thus reducing the gases substantially to room temperature at all times.

The coil 54 opens at its end into a vertical tube 35 60 substantially at its center. The lower end of the tube 60 passes through and is sealed to the bottom of the reservoir 58, and opens outside the reservoir, to discharge excess flue gases from the instrument, and to insure that gases withdrawn 40 for analysis are at atmospheric pressure. The upper end of the tube 60 opens above the level of the reagent 56, and maintains the interior of the reservoir 58 at atmospheric pressure.

45 Mounted on the lower end of the reciprocating connecting rod 20 is a pivot 62 (Figures 9 and 10) adapted to seat in a bearing opening 64 formed in a cast part 66 brazed or soldered to the upper end of a hollow vertical tube 68 sliding in an opening in the top of the reservoir 58. The part 66 is formed with a passage 70 which is normally closed by a screw 72 which locks the pivot in place.

50 Thus detaching the tube 68 from the rod 20 involves removing screw 72 which, as shown in Figure 10, automatically insures that at that time the interior of the tube 68 is at atmospheric pressure, and there is no danger of sucking any of the reagent 56 up into the tube.

The tube 68 is sealed into a novel head 74, of non-corrosive material such as one of the synthetic resins, with an opening in its side in registry with a passage 76 formed in the head. The lower end of the tube 68 opens into, and is sealed to the upper end of, an open-bottom container 78, of synthetic resin or the like.

65 The container 78 which forms the measuring chamber of the sampling device dips into, and at all times has its lower end sealed by, a body of mercury 80 contained in a vessel 82 which is mostly submerged in the reagent 56 to keep the 70 mercury cool, but which of course opens well above the level of the reagent. The vessel 82 is supported by having one side extended upwardly and secured to the top of the reservoir 58.

A vertical tube 84 is sealed into the bottom of 75 the vessel 82, and is arranged at its upper end

telescopically within the lower end of the tube 68. The tube 84 is substantially smaller in diameter than the tube 68, and of course is also considerably smaller in diameter than the opening in the bottom of the container 78.

The head 74 also has sealed thereto at its upper end a vertical tube 86, enough smaller in diameter than the tube 60 to provide a substantial clearance therebetween, and which projects into and forms in effect a telescoping connection 10 therewith. The clearance insures that the reservoir 56 is always at atmospheric pressure.

The tube 86 opens at its upper end into a passage 88 having as a continuation thereof a vertical open tube 90 (Figures 7 and 8) surrounded by 15 a well of mercury 92. The well of mercury 92 is a space which communicates with the passage 76, and it contains a one-way valve in the form of a very light cup-shaped member 94, inverted over 20 the end of the tube 90, and guided by means such as pins 96 so that its lower edge can dip into the mercury 92.

When the member 94 is in the position of Figures 5, 6, and 7, the gas passes freely from passage 88 to the passage 76, without passing through the 25 mercury 92. When the member 94 is in the position of Figures 3 and 8, with its lower edge dipping into the mercury 92, communication between passages 88 and 76 is cut off. As passage 88 is always at atmospheric pressure, and as member 94 30 is very light, a slight suction in passage 76 is sufficient to open the valve.

Also, to insure a minimum of reaction of the gases on the mercury 92, as shown best in Figure 8, the member 94 is very slightly larger than tube 35 90, and has a considerable area subject to suction in passage 76, so that while there is a considerable height of mercury sealing the valve when closed, as in Figure 8, the valve nevertheless opens so quickly that there is substantially no tendency for 40 the gas to bubble through the mercury.

Assuming a point in the cycle illustrated in Figure 3, with the container 78 full of mercury and valve 94 closed, the rod 20 reciprocates upwardly as illustrated in Figure 5, causing a reduced pressure in the container 78 as the mercury runs out of it, opening valve 94 as shown in detail in Figure 7, and drawing in a predetermined amount of gas from the tube 60. It is important to note that by our novel arrangement of the parts described above, this gas is at room temperature and at atmospheric pressure, and therefore for all practical purposes the charge is always not merely the same volume but that this volume is not subject to substantial variations due to temperature and pressure differences.

55 Figure 6 shows the end of the upward stroke, with a full charge of gas measured off. On the down stroke the valve 94 closes the instant the pressure in passage 76 rises to atmospheric pressure, i. e. practically instantly at the end of the stroke, and the mercury 80 forces the measured charge of gas out through the bottom of tube 84.

Tube 84 exhausts the gas, past a weighted lever 98 forming in effect a one-way valve, into the 65 lower end of an upwardly-inclined tube 100, shown as square in cross-section. The part of the lever 98 which normally closes the lower end of the tube 84 is provided with a relatively small opening which cooperates with the edge to break 70 the stream of gas up into a large number of small bubbles, to give a large surface acted on by the reagent.

75 The gas passes up the tube 100, and is discharged into the lower end of a vertical tube 102, 75

opening at its lower end in the reagent 56 and having its closed upper end well above the level of the reagent 56. The tube 102 is shown square in cross section, and as inclosing the upper end of a round-section tube 104. The tube 100 and the square tube 102 of course contain reagent, which acts to absorb the CO₂, so that the gas passing into the tube 104 is the measured quantity of flue gas, minus its CO₂ content.

10 The gas draws a constant stream of fresh reagent into the lower end of tube 100, and circulates it into the square tube 102 in the space around the round tube 104, and allows it to discharge at the lower end of the tube 102. Thus the tube 100 and the tube 102 in effect form a tubular system immersed in the reagent and through which the gas causes the reagent to circulate. This insures that each charge of gas is acted on by fresh reagent.

15 20 The lower end of the tube 104 discharges the residual gas up through a tube 106 into a bell 108 having a connecting rod 110 passing slidably out through a guide or pedestal 112 and having a head 114 above the reservoir. The position of the head 114 is thus dependent, at the end of each cycle when the residual gas is in the bell 108, on the proportion of CO₂ to unabsorbed residual gases.

25 30 At this point in the cycle, cam lever 22 rocks the lever 30 to release (against the resistance of a spring 116, Figure 4) an arm 118 mounted on the shaft 120 of the recorder pen 122, so that an adjustable set-screw 124, carried by an auxiliary arm 126 adjustably threaded into a lug on the arm 118, drops onto the head 114, or is pushed up by the head 114 due to the buoyancy of the gas in bell 108, as the case may be, to give the pen 122 the proper new setting.

35 40 The pen 122 cooperates with a chart 128 (Figure 2) driven by a clock mechanism 130, and which in the arrangement illustrated is covered by a glazed door 132 secured over the chart and pen to the face of the panel 10.

45 45 It will be noted from Figure 4 that rib 32 and lever 30 are provided with clamping parts which grip the arm 118 between them when the cam 22 permits, and which are connected by a clamp bolt 134 on which the spring 116 is sleeved, and which passes through an arcuate slot 136 in the arm 118. As soon as the pin 122 takes up its new position, as described above, the further movement of the cam arm 22 permits spring 116 to clamp the arm 118 (and therefore the pen 122) in the new position until the next cycle.

50 55 In order that variations in the level of the reagent 56 may not affect the positioning of the bell 108, we prefer to have the bell dipping into reagent in a special well shown as a cup-shaped casting 140 secured at its upper end to the top of the reservoir 58 coaxially with respect to the bell 108, and which has sealed into its bottom a vertical tube or standpipe 142 through which the tube 106 extends, and which opens well above the reagent level. The gas carries over enough liquid to keep the well 140 full to a predetermined level determined by overflow openings (too small to show in the drawings).

55 60 After the pen 122 is clamped in its new position, further rotation of the shaft 16 rocks the arm 24 to lower the connecting rod 28. On the lower end of the connecting rod 28 is hung a cup 144 which, when so lowered, dips into the reagent 56 as shown in Figure 5 to be filled to a predetermined level (determined by overflowing openings 146) with reagent. It will be seen that the cup is al-

ways filled to the same level, regardless of variations in the level of the reagent 56.

The lowering of the cup 144 unseals a goose-neck end on an exhaust conduit 148 which communicates with the lower end of the pipe 106, 5 whereupon the weight of the bell 108 pushes the measured residual gas out into the top of reservoir 58, whence it escapes through the vertical pipe 60 and through any clearances that may exist where parts 52, 68, 28, and 110 pass through 10 the top of the reservoir.

15 Before the next charge of gas is emptied into the bell 108, the cup 144 is again lifted to seal the exhaust pipe 148. Since the cup 144 is always filled to the same level, any back pressure on the bell 108 is always the same, and can be calibrated for.

20 The three pipes 148, 104, and 106 are shown connected at their lower ends to a common drain 150 controlled by a suitable manually-operable valve 152. The conduit 148 may have welded to the bend at the top a stamped bracket or hook 154, to engage the bail 156 which connects the cup 144 to the rod 28, so that when the latter is disconnected the cup 144 will not fall into the re- 25 agent 56.

25 30 By disconnecting a joint 158 in the conduit 52, and disconnecting the rods 20 and 28 as already described, the reservoir 58 with all the apparatus associated with it can be removed as a unit, for 30 convenience of repair and calibration.

35 40 In operation, the instrument follows a regular cycle, gas being continuously cooled in the coil 54 or its equivalent and discharged into the pipe 60, predetermined quantities being measured off 35 by reciprocating the head 74 and discharged into the reagent in the inclined tube 100, the residual quantities being measured by the bell 108 and the pen 122 automatically reset accordingly, and the measured gases being finally discharged through 40 the conduit 148.

45 50 While one illustrative embodiment has been described in detail, it is not our intention to limit the scope of the invention to that particular embodiment, or otherwise than by the terms of the 45 appended claims.

We claim:

1. An instrument comprising a source of supply of gas, a reservoir for a liquid reagent, a coiled conduit receiving gas from said source and 50 which is submerged in the reagent, a volume measuring device above the reagent, an upright tube passing through the reagent and receiving gas from the conduit and which communicates at its lower end with the exterior of the instrument and 55 which communicates at its upper end with said volume measuring device, means for passing through the reagent successive quantities of gas measured by the volume measuring device, and measuring means for determining a character- 60 istic of said quantities of gas after treatment thereof by said reagent.

2. A gas measuring device for use in an instrument comprising a stationary vessel open at its top and containing mercury and which has a tube 65 extending vertically through the mercury and through the bottom of the vessel and joined to said bottom by a mercury-tight joint, and a vertically reciprocating head including a depending open-bottom gas container with its top provided 70 with means forming a telescoping joint with the upper portion of said vertically-extending tube, said telescoping joint having a substantial clearance so that gas may pass into and out of said container around said tube, said head having one- 75

- way gas-controlling valve means so that gas is drawn into the container past the valve means when the head is lifted to withdraw the container from the mercury and is forced by the mercury from the container down through said tube when the container is forced downwardly into the mercury.
3. A gas analyzer comprising a reservoir containing a liquid reagent, a stationary vessel open at its top and containing mercury and which is mainly submerged in the reagent to cool the mercury but the open top of which is above the surface of the reagent and which has a tube extending vertically through the mercury and through the bottom of the vessel and joined to said bottom by a mercury-tight joint and which opens at its lower end in said reagent, a vertically reciprocating head including a depending open-bottom gas container with its top provided with means forming a telescoping joint with the upper portion of said vertically-extending tube, said telescoping joint having a substantial clearance so that gas may pass into and out of said container around said tube, said head having one-way gas-controlling valve means so that gas is drawn into the container past the valve means when the head is lifted to withdraw the container from the mercury and is forced by the mercury from the container down through said tube when the container is forced downwardly into the mercury, an upwardly inclined guide submerged in and filled by the reagent and into the lower end of which the bottom of said tube opens, and a device receiving the treated gas from the upper end of said guide and determining a characteristic thereof.
4. A gas measuring device for use in an instrument comprising a reciprocable head having depending therefrom a gas intake tube and an open-bottomed gas measuring container, and having a passage leading from the tube to the interior of the container and which is provided with a one-way valve controlling said passage, said valve including an upwardly opening tube having a well

of mercury surrounding its base, together with a cup-shaped member inverted over said tube with the lower edge of its wall dipping into the mercury in said well.

5. Gas treating apparatus comprising a reservoir containing liquid, a liquid containing well in the reservoir, a gas-measuring bell dipping into the liquid in the well, sampling means for periodically discharging into said bell quantities of gas to be measured, exhaust means for the gas having an inlet tube projecting upwardly into said bell and opening therein above the level of the liquid in the well and having an outlet tube with its end facing downwardly above the level of the liquid in the reservoir, a vertically reciprocated cup and means operated synchronously with the sampling means to lower the cup into the liquid in the reservoir to be filled thereby to a predetermined level and at the same time to leave said downwardly facing end of the outlet tube unobstructed while exhausting gas which has been measured and to be raised to seal said end in the liquid in the cup while supplying the said gas to be measured, said sealing liquid always rising to the same level in said tube.

6. Gas analyzing apparatus comprising a reservoir containing a reagent, an upwardly sloping tube immersed in and filled by said reagent, an upright tube connected to the upper end of the sloping tube and having its lower end terminating below the reagent level and its upper end above the reagent level, sampling means to discharge a measured quantity of gas to be analyzed into said sloping tube adjacent the lower end thereof so that gas rising through the sloping tube into the upper part of the upright tube causes circulation of reagent from the reservoir through the sloping tube and back to the reservoir through the lower end of the upright tube and means connected to the upper end of the upright tube to measure the gas rising therethrough.
